UNITED STATES PATENT OFFICE.

SIMON RUDOLPH OPPENHEIM, OF KEELER, CALIFORNIA.

APPARATUS FOR INCINERATING KELP AND LIKE MATERIALS.

1,282,708.

Specification of Letters Patent.

Patented Oct. 22, 1918.

Application filed June 7, 1917. Serial No. 178,371.

To all whom it may concern:

Be it known that I, SIMON RUDOLPH OPPENHEIM, a citizen of the United States, residing at Keeler, in the county of Inyo and State of California, have invented a new and useful Apparatus for Incinerating Kelp and like Materials, of which the following is a specification.

This invention relates to the incineration or charring of kelp and like materials, and the main object of the present invention is to provide an improved method of incineration or charring requiring minimum expenditure of fuel and enabling extremely rapid and economical incineration of the kelp.

Another object of the invention is to provide for continual removal of the incinerated or charred material from the furnace in such manner as to prevent combustion of any carbon or char remaining in such material.

A further object of the invention is to facilitate the utilization of volatile by products, such as ammonia, tar and creosote.

The accompanying drawings illustrate an embodiment of my invention and referring thereto:

Figure 1 is a side elevation of the incinerator with the gas scrubber connected thereto, parts of the apparatus being shown in section.

Fig. 2 is an end elevation with parts broken away.

Referring to the drawings, the incinerator shown, comprises a furnace having closed side, top and end walls of masonry or other suitable material and formed with any desired number of elongated horizontally extending incinerating chambers 2, and closed at each end by the end walls 3. Charging doors 6, are provided in the roof or top of each chamber 2. Each chamber is provided at one side with any desired number of firing doors 9 in its side wall 4. A gas outlet main 10 extends vertically at one end of the furnace and has two ducts 11 and 12 extending into the chamber 2 at different heights and is also connected to a branch main 13 extending alongside the furnace and having ducts 15, extending into an elongated longitudinally extending chamber or ash pit 19 below the chamber 2, a number of dumping grates 20 being preferably provided at the bottom of chamber 2 and over the chamber 19, so as to support the kelp in chamber 2. Ducts or branch pipes 15 are

provided with closure means or gates 15'. The bottom of each chamber 19 is formed with inclined side walls so as to form a trough, and in the bottom of said trough a screw conveyer 23 operates, said screw conveyer extending the full length of the furnace and being preferably prolonged at one end, so as to extend outside of the ash pit and within a casing 25, to enable cooling of the incinerated material, such as ash or char, before it is exposed to the air, said casing being partly water-jacketed, as at 25'.

The gas outlet main 10 may be connected to any suitable means for drawing off the gases and means are preferably provided for removing tar or other valuable materials from the gases. For this purpose, said main may be connected to the washer indicated at 28, consisting of a closed tank having partitions or baffle plates 29 and 30 extending alternately from its top and bottom so as to cause the gas passing through the scrubber to take a tortuous path between said partitions and over water or liquid indicated at 31 in the bottom of the tank. An outlet pipe 32 leads from said tank to a fan or blower 33 for maintaining draft through the apparatus and forcing the gases to an outlet flue 34. The branch pipe 13 aforesaid, is preferably given a slight dip toward the discharge end, so that any tar or other material condensed therein will drain off to the washer.

The operation is as follows: The kelp or other material to be incinerated is charged into the chambers 2, through the doors 6, which are then closed, and suitable liquid fuel such as distillate, is sprayed on to the top of the mass of kelp, by means of a hose, or otherwise, the streams and jets of liquid fuel from such hose being applied through the furnace doors 9, which are opened sufficiently for that purpose, as well as for admitting air for combustion, and fan 33 is operated to draw air through the chamber 2, such air passing from suitable openings left in the fire doors 9 or elsewhere, and passing first through one or both of the upper ducts 11 and 12 until the fire is well started, said ducts being then shut off by their valves 11' and 12' and the valves for ducts 15 being opened so that the air is drawn downwardly through the mass of kelp in chamber 2 and out through ducts 15, so that the whole body of kelp is eventually burned to convert it either to char or to ash.

as may be desired. The hot gases resulting from this combustion pass off through the washer 28, wherein any solid or liquid material carried in such gases is collected, and said 5 gases are then discharged through blower 33 and outlet flue 34. In passing between the baffles 29 and 30 of the washer, the rapidly moving gases are forced into contact with the water in said washer, and more or less 10 agitation of the water is thereby produced, so that effective contact of the gas with the water is secured. The ash or char collects in the trough 21 in the bottom of chamber 2, and is continually forced out by screw 15 conveyer 23, through the casing 25, wherein it is cooled before it is exposed to the outer air, this being particularly desirable in the case of char, as it prevents further burning 20 of the char by reignition on such exposure.

20 What I claim is:

1. An apparatus for incinerating or charring kelp or like material comprising a furnace provided with an elongated horizontally extending combustion chamber, an 25 elongated horizontally extending ash pit below said combustion chamber, and a grate between said combustion chamber and ash pit, said combustion chamber being provided with charging doors in its top and 30 with firing doors in its side, and said ash pit having its bottom formed as a trough and a conveyer working in said trough to move the ash or char longitudinally therein and discharge same from the furnace, a gas outlet conduit having valved communication 35 with the combustion chamber, and valved communication with the ash pit, whereby gases may be drawn directly from the combustion chamber, or from the ash pit so as

to cause downdraft through the material on 40 the grate, a washing means connected to said conduit for collecting material carried over with the gases therein, and an exhaust fan connected to draw the gases through said 45 conduit and washing means.

2. An apparatus for incinerating or charring kelp or like material comprising a furnace provided with an elongated horizontally extending combustion chamber, an 50 elongated horizontally extending ash pit below said combustion chamber, and a grate between said combustion chamber and ash pit, said combustion chamber being provided with charging doors in its top and with firing doors in its side, and said ash 55 pit having its bottom formed as a trough and a conveyer working in said trough to move the ash or char longitudinally therein and discharge same from the furnace, a gas outlet conduit having valved communication 60 with the combustion chamber, and valved communication with the ash pit, whereby gases may be drawn directly from the combustion chamber, or from the ash pit so as to cause downdraft through the material on 65 the grate, a washing means connected to said conduit for collecting material carried over with the gases therein, and an exhaust fan connected to draw the gases through said conduit and washing means, said conduit being inclined downwardly from its connection with the ash pit toward the washer to cause liquid material therein to 70 drain to the washer.

In testimony whereof I have hereunto set 75 my hand at Keeler, California, this 21st day of May, 1917.

SIMON RUDOLPH OPPENHEIM.
